Int. Cl. D7—05

U.S. CL. D49—1 C

FIG. 2

FIG. 1

FIG. 3

FIG. 1 is a top plan view of a clothes scrubbing device for attachment to a washing machine lid, showing my new design;

FIG. 2 is a side elevational view thereof, taken partly in section on line 2—2 of FIG. 1; and

FIG. 3 is a top perspective view thereof.

The portions of a washing machine lid shown in broken lines in FIG. 1 are for illustrative purposes only, and form no part of the claimed design.

I claim:

The ornamental design for a clothes scrubbing device for attachment to a washing machine lid, as shown and described.
